DESIGN FOR A BOTTLE

Edward J. Schuellein, New York, N. Y., assignor
to Schenley Distillers Corporation, New York,
N. Y., a corporation of Delaware

Application June 22, 1939, Serial No. 85,635

Term of patent 14 years

To whom it may concern:

Be it known that I, Edward J. Schuellein, a citizen of the United States, residing at New York, county of New York, and State of New York, have invented a new, original, and ornamental Design for a Bottle, of which the following is a specification, reference being had to the accompanying drawing, forming a part thereof.

I claim:
The ornamental design for a bottle, as shown.

EDWARD J. SCHUELLEIN.
